UNITED STATES PATENT OFFICE.

GEORGE H. W. RUNGE, OF ST. LOUIS, MISSOURI.

LUBRICATOR.

SPECIFICATION forming part of Letters Patent No. 636,185, dated October 31, 1899.

Application filed March 8, 1899. Serial No. 708,260. (No model.)

To all whom it may concern:

Be it known that I, GEORGE H. W. RUNGE, a citizen of the United States, residing at the city of St. Louis, in the State of Missouri, have 5 invented certain new and useful Improvements in Lubricators, of which the following is a full, clear, and exact description, reference being had to the accompanying drawings, forming part of this specification.

10 My invention relates to a lubricator by means of which a continuous feed of oil may be effected through various conductors leading to various points, the flow of oil being maintained by means of compressed air and 15 spring-pressure exerted thereon.

My invention consists in features of novelty hereinafter fully described, and pointed out in the claims.

Figure I is a perspective view showing my 20 improved lubricator. Fig. II is a vertical sectional view taken through the oil-reservoir and compressed-air chamber.

1 designates an oil-reservoir having an inlet 2, closed by a cap 3. To the lower end 25 of this reservoir is fixed a discharge-pipe 4.

5 designates a chamber into which air may be introduced and compressed, the said chamber having communication with the reservoir 1 by a connecting-pipe 6. The chamber 5 is 30 supported by a cross-piece 7 and the connecting-tube 6.

Within the chamber 5 is a piston 8, supported on a coil-spring 9, that rests upon a removable cap 10, secured to the lower end 35 of the chamber. At the upper end of the chamber is a nipple 11, the end of which is closed by a removable cap 12, and from this nipple into the interior of the chamber communication is controlled by a spring-controlled 40 check-valve 13, that prevents the escape of air from the interior of the chamber after it has been forced therein by means of a suitable pump applied to the nipple 11 on the removal of the cap 12. The pipe 4 contains a valve 14.

45 15 designates cocks that may be located in any desirable positions where there are journals to be lubricated, these cocks being provided with set-valves 16, by which the quantity of oil flowing through the cocks may be controlled to a nicety, so that any desired feed of oil may be attained. The cocks are

connected by delivery-pipes 17, leading thereto, and the said delivery-pipes are fed by a supply-pipe 18, that leads to the outlet-pipe 4. 55

In the supply-pipe 18 are bends 19 and 20. Between the bends 19 and 20 is a union 21, containing a turn-joint the sleeve of which is held in place by a set-screw 22. The pipe 18 is connected to the discharge-pipe 4 by a 60 union 23, containing a turn-joint the sleeve of which is held in place by a set-screw 24. By providing the bends 19 and 20 in the supply-pipe 18 and introducing the loose unions 21 and 23, that provide for a universal movement of the parts with relation to each other, either part may be mounted on a movable support without the moving of such support effecting the operation of the device.

This lubricator is well adapted for use in 70 supplying lubricant to the journals of car-

axles, or it may be used in lubricating journals of any other description. The coupling 18^a of the supply-pipe 18, by which it is joined to the delivery-pipes 17, is provided with an 75 extra arm 18^b, by which a second set of cocks may be connected by suitable piping to the supply-pipe 18 and be fed therefrom.

In the operation of this lubricator the reservoir 1 is filled with oil and air is pumped 80 into the air-chamber 5, so as to be compressed therein, by attaching a pump to the nipple 11 on the removal of the cap 12. In compressing the air into the chamber 5 the piston 8 is forced downwardly, contracting the spring 85 9 and moving the piston to the lower end of said chamber. The valve 14 is then opened when it is desired to start the flow of oil to the cocks 15, and the pressure of the compressed air flowing from the chamber 5 90 through the pipe 6 into the oil-reservoir presses the oil out of the reservoir gradually, causing it to flow through the pipes 4, 18, and 17 to the cocks 15 and feeding it to the journals to be lubricated. 95

I claim as my invention—

1. A lubricator comprising an oil-reservoir, a discharge-pipe leading from the reservoir, a compressed-air chamber, a pipe of less diameter than the reservoir and chamber, connecting the compressed-air chamber with the oil-reservoir, and the spring-piston located within the compressed-air chamber; substantially as described. 100

2. A lubricator comprising an oil-tube having an inlet at the upper end of the tube, a cap closing the inlet, a discharge-pipe fixed to the lower end of the oil-tube, an air-tube having a nipple at the upper end of the air-tube, a cap closing the nipple, a spring check-valve controlling the nipple, the cap closing the lower end of the air-tube, the spring seated on the lower cap, the piston supported on the coil-spring, and the pipe connecting the upper ends of the oil-tube and air-tube and of less diameter than the said tubes; substantially as described.
